UNITED STATES PATENT OFFICE.

HERMANN HAUSSMANN AND SOLA B. DUNN, OF CHICAGO, ILLINOIS.

ECRASEUR.

SPECIFICATION forming part of Letters Patent No. 511,202, dated December 19, 1893.

Application filed December 24, 1892. Serial No. 456,225. (No model.)

To all whom it may concern:

Be it known that we, HERMANN HAUSSMANN and SOLA B. DUNN, citizens of the United States, residing at Chicago, in the county of Cook and State of Illinois, have invented certain new and useful Improvements in Ecra-
5 seurs, of which the following is a full, clear, and exact specification.

Our invention relates to that class of ecra-
10 seurs which employ a looped chain or noose adapted to be actuated by a screw arranged in the stock or tube of the instrument.

The primary object of our invention there-
15 fore is to provide improved and simple means for readily taking up the slack of the chain or noose independently of the screw.

With these ends in view, our invention con-
20 sists in certain features of novelty in the con-
struction, combination and arrangement of
25 parts hereinafter described in connection
with the accompanying drawings and more
particularly pointed out in the claims.

In the said drawings, Figure 1, is a side ele-
25 vation of our improved instrument. Fig. 2,
is a plan view thereof. Fig. 3, is a vertical
longitudinal section, the handle and screw
30 being shown in full lines, and Fig. 4, is a de-
tail view illustrating a modification herein-
after described.

35 Like signs of reference indicate like parts throughout the several views.

A, is the ecraseur stock or tube which may
be of the ordinary or any suitable construc-
35 tion having the keeper or loop B, at one end
and being provided throughout the greater
portion of its length at its upper side with a
slot C, and opposite such slot on the under
side with a suitable handle or finger ring D.

The screw E having a suitable operating han-
40 dle F, is arranged within the stock or tube A,
as heretofore, but instead of being longitudi-
nally movable therein, it is so secured as to
be capable of rotary movement only. This
is preferably accomplished by providing the
45 stem of the handle F with an annular groove
G, over which fits a milled collar H, having a
removable screw or pin I engaging in the
groove G, so as to permit the handle F and
the screw E to rotate independently of the
50 collar H. The collar H has an angular slot
J, while the tube or stock A is provided with
a pin K, which slot and pin constitute a bayo-

net joint for removably securing the collar H
to the stock A. Instead of this arrangement
for holding the screw against longitudinal 55
movement, the same object may be accom-
plished by providing the end of the screw with
an annular groove G', and driving a short
screw or pin I' through the side of the stock
or tube into such groove, as shown in Fig. 4, 60
whereby the screw will be held against slip-
ping out of the stock, but will be permitted
to rotate freely therein. It is desirable how-
ever that the screw should be so held as to
be capable of being readily removed for clean- 65
ing the device, and therefore the bayonet
joint above described is the preferred form.

The chain or noose L which passes through
the keeper B, as usual, is secured to a slide
M. This attachment may be effected in any 70
suitable manner, but we prefer to accomplish
it by providing the ends of the chain with
enlarged heads N, which are fitted into com-
plementary sockets or slots having enlarged
inner ends formed in the face of the slide M, 75
so that when the heads N are in place in their
respective sockets they will be held against
longitudinal displacement, while the perpen-
dicular or outward movement of the heads
may be prevented by a flat button O having 80
a stem O' threaded in the slide M between
the heads N, so that when it is turned across
such heads, as shown in Fig. 2, it will serve
to hold the latter in place.

The slide M is provided on its under side 85
with a narrowed portion P which projects
into the slot C in the stock, and carries on its
under side two sleeves or collars Q which fit
the contour of the inner side of the tube or
stock and thus serve to guide the slide, two 90
collars being employed for the sake of greater
rigidity. The inner surfaces of these collars
Q are plain, and the screw E projects freely
through them, and pivoted to the slide at R
between these collars is a dog S which pro- 95
jects through the slot C, and is provided at
its under side with a series of teeth comple-
mentary to and engaging with the thread of
the screw E, the dog being held normally in
engagement with the screw by means of a 100
suitable spring T interposed between the slide
and the thumb piece of the dog. The pivot
R of this dog is so arranged, that is to say at
its rear end, that the slide may be drawn back-

ward or away from the keeper B to take up the slack in the chain, without previously lifting the dog from engagement with the screw. It will be seen however, that the reverse movement of the slide must be effected by the rotation of the screw, or else by first raising the dog out of contact therewith.

With an instrument thus constructed it will be seen that the same may be conveniently held by one hand of the surgeon. The dog S being arranged opposite the handle D it is convenient to the thumb and may be readily slipped back and forth for taking up the slack of the chain or noose independently of the screw.

Having thus described our invention, what we claim as new therein, and desire to secure by Letters Patent, is—

1. In an ecraseur, the combination with a slotted stock, a revoluble screw secured against longitudinal movement therein, and the noose or chain, of a pivoted dog secured to said noose

or chain and having a thumb piece arranged on the exterior of said stock and a toothed portion projecting through said slot and engaging said screw, and means for holding said dog up to its work when in engagement with said screw, substantially as set forth.

2. In an ecraseur, the combination of a slotted stock or tube, a slide having a sleeve or collar arranged in and fitting against the inside of said stock or tube and constituting a guide for said slide, a screw held against longitudinal movement, passing loosely through said sleeve or collar, a dog carried by said slide and engaging said screw, a spring for holding said dog normally in engagement with said screw, and the chain or noose secured to said slide, substantially as set forth.

HERMANN HAUSSMANN.

SOLA B. DUNN.
